CLAIM

The ornamental design for a refrigerator, as shown and described.

DESCRIPTION

1. Refrigerator
Reproduction **1.1** is a front perspective view of the refrigerator;
Reproduction **1.2** is a front view thereof;
Reproduction **1.3** is a back view thereof;
Reproduction **1.4** is a left view thereof;
Reproduction **1.5** is a right view thereof;
Reproduction **1.6** is a top view thereof;
Reproduction **1.7** is a bottom view thereof;
Reproduction **1.8** is a reference view showing the status in which the inside can be seen through the front glass;
Reproduction **1.9** is a reference view showing the state in which the outer door has been opened;
Reproduction **1.10** is a reference view showing the use state in which the mini-table has been unfolded; and
Reproduction **1.11** is a reference view showing the outer door and inner door have been opened.

(Continued)

The broken lines depict portions of the refrigerator that form no part of the claimed design; the fine lines on the drawings indicate the flat surface, curved surface or transparent materials.

1 Claim, 11 Drawing Sheets
